(57) **CLAIM**

The ornamental design for a fire tornado lamp, as shown and described.

DESCRIPTION

FIG. 1 is a perspective view of fire tornado lamp showing my new design;

FIG. 2 is a front elevation view thereof, the rear elevation view being a mirror image of the front elevation;

FIG. 3 is a right elevation view thereof, the left elevation view being a mirror image of the right elevation;

FIG. 4 is a top plan view thereof;

FIG. 5 is a bottom plan view thereof;

FIG. 6 is a perspective view of another embodiment of the lamp, the only difference being that a top portion of the lamp is generally transparent;

FIG. 7 is a front elevation view thereof, the rear elevation view being a mirror image of the front elevation;

FIG. 8 is a right elevation view thereof, the left elevation view being a mirror image of the right elevation;

FIG. 9 is a top plan view thereof; and,

FIG. 10 is a bottom plan view thereof.
